UNITED STATES PATENT OFFICE

RICHARD ERWIN FAWN, OF CLEVELAND, OHIO, ASSIGNOR TO THE B. F. GOODRICH COMPANY, OF NEW YORK, N. Y., A CORPORATION OF NEW YORK

DESIGN FOR A HOT-WATER BOTTLE

Application filed March 14, 1930. Serial No. 34,858. Term of patent 14 years.

To all whom it may concern:

Be it known that I, RICHARD ERWIN FAWN, a citizen of the United States, residing at Cleveland, in the county of Cuyahoga and State of Ohio, have invented a new, original, and ornamental Design for a Hot-Water Bottle, of which the following is a specification, reference being had to the accompanying drawing, forming a part thereof.

The accompanying drawing shows a front elevation of a hot water bottle embodying my new design, the reverse side of the bottle having the same appearance as that of the side here shown.

I claim:

The ornamental design for a hot water bottle as shown and described.

RICHARD ERWIN FAWN.
